INVENTOR.

United States Patent Office.

DESIGN FOR A COACH LAMP.

EDWIN BLAKESLEE, OF NEW HAVEN, CONNECTICUT, ASSIGNOR TO
C. COWLES & CO., OF THE SAME PLACE.

Design No. 2,506, patented November 20, 1866.

SPECIFICATION.

TO ALL WHOM IT MAY CONCERN:

Be it known that I, EDWIN BLAKESLEE, of New Haven, in the county of New Haven, and State of Connecticut, have invented a new Design for a Coach Lamp. And I do hereby declare the following, when taken in connection with the accompanying drawing and the letters of reference marked thereon, to be a full, clear, and exact description of the same, and which said drawing constitutes part of this specification, and represents in—

Figure 1 a side view; and in—

Figure 2 the lights detached as for the subject of this design.

This invention relates more particularly to the form of the lights than to other parts of the lamp, and in this peculiar form the design consists.

To enable others skilled in the art to manufacture my new design, I will proceed to describe the same as illustrated in the accompanying drawing.

A is the socket, *B* the body, and *C* the top; the socket and top being no essential part of the design, may be of any form or configuration.

The lights *D*—alike upon as many sides as lights are placed—are of an octagonal form, that is to say, a diamond form having the four points cut off, and so as to form an angular corner, *E*, at each of the four long sides of the light *D*, and into which angular corner other lights are placed to finish or fill the corner, as more clearly seen in fig. 2, the angular lights *E* being shown detached from the principal light *D*.

What I claim, therefore, as my invention, is the herein-described design for the main lights *D*, and the corner lights *E* of the form described and shown for a coach lamp.

EDWIN BLAKESLEE.
